UNITED STATES PATENT OFFICE.

VIRGINIA MARIE ELLIOTT, OF CHICAGO, ILLINOIS.

KIMONO.

1,211,832.

Specification of Letters Patent.

Patented Jan. 9, 1917.

Application filed April 14, 1916. Serial No. 91,007.

To all whom it may concern:

Be it known that I, VIRGINIA MARIE ELLIOTT, a citizen of the United States, and resident of Chicago, in the county of Cook and State of Illinois, have invented certain new and useful Improvements in Kimonos, of which the following is a full, clear, and exact specification.

This invention relates generally to improvements in kimonos heretofore consisting of strips of textile fabric cut on the bias for shaping purposes, and secured together by a number of seams, and as a result of which there is unavoidably a stretching and sagging of the easily stitched fabric throughout the angle of the bias producing an unevenness in the bottom edge of the skirt, a pull wrinkling the fabric along the seam, and accordingly distorting the fabric, whereby the garment as a whole is not only disfigured in appearance, but impossible of being ironed in a uniformly smoothed condition when laundried.

My invention more specifically however, relates to improvements in kimonos when so constructed from thin, soft, draping materials, commonly used for negligées, and especially when made of crêpe de chine, and similar materials ornamented with ribbon in the form of bows stitched together, and to the fabric, and in which the objections above enumerated due to bias cutting and the use of seams are accentuated by reason of the flimsy character of the material, and the laundering of which requires the ripping of the ribbon bows from the garment, and apart for separate laundering, subsequent re-forming, and that they be re-located and again stitched to the garment. The practice, skill and time required for accurately cutting on the bias such thin and flimsy materials, stitching them together in the form of seams, separately stitching each of the several bows of ribbons together, and to the garment, and for washing and ironing such a kimono as best may be, is obviously objectionable, and therefore makes apparent that any means by which it is possible and practical to successfully construct a kimono dispensing with these objectionable features, will be a substantial and material advance in the kimono art.

The object of my invention broadly stated, is to provide a means by which a kimono may be successfully constructed from a single strip of any material, and

particularly from crêpe de chine, and similarly flimsy materials, in the absence of any bias cut, waste of material and seams, and by which the ribbons for stitchless decorative bows are utilized for shaping and maintaining the garment in shape upon the wearer.

More specifically stated, the object of my invention is to provide a means by which a kimono may be constructed from a folded single strip of thin, soft fabric, with ribbon bows, the ribbon for which furnishes a practical substitute for seams heretofore employed for securing the back, front and other parts of the garment together, and for bias cuts for shaping the garment to the wearer.

A further object of my invention is to provide a means by which a kimono may be successfully constructed from a single strip of material, and with a decorative collar formed integral therewith.

Another object of my invention is to provide a kimono which is seamless in its entirety, and which may be decorated with unstitched bows of ribbon detachably connected with the fabric of the kimono in such a manner that they may be conveniently and quickly removed therefrom, and with the material of the body of the kimono cleansed and ironed in an outstretched position, and therefore with perfect and uniform smoothness.

A further object of my invention is to provide a means by which it is possible and practical to successfully, consecutively complete the construction in a single strip of material of kimonos of the required length, limited in numbers only to the length of the strip before severing the same therefrom, whereby the opposing split edges of two kimonos may be simultaneously hem-stitched with one and the same stitch, and be picoted when severed from each other, and a corresponding saving of time and material be effected for their construction.

With these ends in view, my invention finds embodiment in certain features of novelty in the construction, combination and arrangement of parts by which the said objects and certain other objects are attained, all as hereinafter fully described with reference to the accompanying drawings, and more particularly pointed out in the claims.

In said drawings: Figure 1 illustrates in plan view a single strip of textile fabric pro-

vided with means from which to construct a kimono in which my invention finds its embodiment. Fig. 2 is about a three-quarter back view of the kimono in its operative position upon the wearer. Fig. 3 is a similar front view of the same. Fig. 4 is a central longitudinal section of the blank in its folded position. Fig. 5 is a transverse section of the same showing the bows and their location 10 for connecting the outer side edges of the folded fabric. Fig. 6 is a plan view of an uncut strip of fabric showing the adaptability of my invention for simultaneously picotting the bottom edges, and the opposing 15 edges of the front opening with a single line of stitching for each of two kimonos, and Fig. 7 is an enlarged detail diagrammatic view showing hemstitching and also the picotting of the opposing edges of the fabric 20 on splitting the hemstitching as hereinafter described.

Similar characters of reference indicate the same parts in the several figures of the drawings.

25 In Fig. 1 is illustrated a rectangular strip of soft thin material preferably crêpe de chine as it is cut from the bolt, which in the construction of a kimono is folded upon the dotted line 6 for forming the back 7 and the 30 front 8, the front being divided upon the line 9.

The back part 7 for a little more than half the length beginning at its end is provided with pairs of slits at intervals of each other 35 adjacent the longitudinal edges of the back for forming horizontal loops 10, similar loops 11 being likewise formed in the front part 8, and so that on folding the fabric the slits forming the several loops will register 40 with each other for the passage of short pieces of ribbon, which after being passed through the slits in such a manner as to conceal the loops, are then tied at their ends in the form of bows, and preferably as 45 shown in Figs. 2 and 3.

The back piece 7 of the strip of cloth is provided adjacent its opposite edges with a pair of slits forming vertical loops 13—13, as is also the front 8 to provide vertical loops 14—14, the slits for which vertically arranged loops 13 and 14 are respectively located about the same distance from and on each side of the folding line 6, and whereby the vertical loops at opposite sides of the line 50 6 are adapted to register with each other for the passage therethrough of a belt or ribbon sash 15 at the waist line of the wearer and through similarly formed vertically arranged loops 16—16, the location of which loops 16—16 is such that they are in a plane substantially above the waist line as shown in Fig. 2.

The front portion 8 in the finished kimono, is also divided on the line 17 extending at a 65 right angle to and crossing the line 9 for

forming the neck opening and providing from the four corner pieces 18 thus produced a collar, the size of the neck opening depending upon the length of the line 17 and its distance from the folding line 6.

For the construction of a collar the four corner pieces are each provided at their points with slits adapted to register with each other and form loops 19—20 whereby the corner pieces may be secured to the fabric 70 of the garment and ornamented with ribbons passing outwardly through the slits and knotted to form bows 21. In this connection it is to be observed that for securing together and ornamenting the longitudinal 75 edges and selvage of the folded rectangular piece of fabric in its operative position for a kimono, the several pieces of ribbon at intervals thereof have their ends passed through the slits in the back part and thence 80 through the registering slits in the front part of the garment, and tied in a bow knot, but in practice the ribbons are first given a turn once around the loops in the back part 85 of the garment, and as may be also around 90 the loop in the front of the garment, to prevent their accidental detachment and relieve the bows of any strains otherwise tending to draw them too tight, or from coming apart.

95 For attaching the sash or belt 15 and locating it in its operative position upon the garment, it is preferably passed loosely through the loop 16 at the back of the garment, and once around the loops 13 in the front piece 100 of the garment, the ends of the sash being tied at the front of the wearer, as shown in the drawings, to form an ornamental bow knot 22, terminating in loose ends forming streamers 23 not only for ornamental purposes, but for confining the kimono to the 105 waist of the wearer.

The turn of the belt ribbon or sash once 110 clear around and out again through the under-arm slots not only prevents the belt 115 from becoming unfastened from the garment, accidentally mislaid, and perhaps lost, but provides a means by which a belt serves for retaining the back of the garment to the proper fullness, and so that whether the belt 120 is tied or untied in front, it operates to draw and shape the garment in a modish and becoming manner without drawing on the sleeves, a result heretofore attained only when the sleeves of a kimono are formed of a piece separate from the body of the garment.

125 With the loops 16 located with reference to the waist line of the wearer of the kimono and the slits 13 and 14, it will be seen that the force from tightening the sash or belt 15 as may be, not only operates to draw the garment to the form of the back of the wearer, and in such a manner as to produce a draping of the fold in the mate-

rial along the shoulder line, but to the form of a kimono sleeve 24 projecting outwardly over the arm of the wearer to a point well toward the elbow, both when the arm is raised, as in Fig. 2, and when lowered as shown in Fig. 3.

It is also here to be noted that by locating the loops in the opposite sides of the garment inwardly some distance away from

10 the edges, to form the base of the sleeve (as shown in the drawing) the arms of the wearer may be freely lifted, and which they would not be were the slots located next the opposing selvage edges.

15 The use of loops formed by parallel slits or openings adapted for the passage therethrough of pieces of ribbon for securing together the opposing selvages of the garment, shaping it, etc., provides for securing

20 an important result attributable to my invention, namely that of utilizing hemstitching as a means not only for forming every slit in the material of the garment and protecting their edges against raveling;

25 but for picotting such edges and accordingly giving them a finished and ornamental appearance, and which is particularly both important and desirable when the material of the garment is made of thin and very

30 flimsy material, and such as is employed more commonly than any other material for the construction of kimonos. In other words when constructing a kimono in which

35 my invention finds embodiment, the single strip of material from which it is formed is first hemstitched along the lines for the slits forming the ribbon loops, and also along the lines 9 and 17 for the front and neck opening, as diagrammatically illus-

40 trated at 25 in Fig. 7, followed by splitting the hemstitching, that is to say the connecting or bridging threads 26 thereof as indicated in the same figure, and thereby picotting the edges of said several slits.

45 It will now be observed that my invention provides for the use of a single strip of fabric, the longitudinal edges of which are provided with a selvage requiring no finishing, that all slits therein may be pro-

50 duced by first hemstitching and then picotting and accordingly ornamented, and that a single line of hemstitching for the front and neck openings when split serves to

55 picot the opposing edges thereof, and that the cut ends of the fabric may be similarly prevented from raveling and ornamente-

60 lly finished in the same manner. Furthermore as illustrated in Fig. 6, my invention provides a means for completing the hemstitch-

65 ing as and for the purposes described throughout a single bolt of cloth of sufficient length for several and a large number of kimonos before severing the cloth into their several lengths, and whereby a

therethrough, when split, serves as a means for picotting at one operation the adjacent ends of two garments.

My invention also makes it practical and possible to finish the hemstitching before severing into lengths a number of garments, the numbers of which are limited only by the length of the cloth in the bolt, and thereby correspondingly reducing the cost of the construction of kimonos, the material of which on being severed from the bolt requires only the splitting of the hemstitching for protecting and picotting the otherwise raw edges thereof, ready for assembling by means of pieces of ribbon as hereinafter described. In other words, it will now be apparent on referring to Fig. 6 of the drawings, that a transverse single line of hemstitching 27 provides a means for picotting the bottom edge of both front end pieces 28, for which 29 is the back part; that the line of hemstitching 30 indicates the dividing line upon which the fronts of two kimonos are to be divided and thereby picotted, and that the transversely hemstitched lines 31 and 32 toward the opposite end of the line of hemstitching 30 when split operates to picot the remaining edges of the collar for the neck opening of two kimonos. In short it is made possible and practical by my invention for a single operator of a sewing machine to provide an uncut bolt of cloth of unlimited length with hemstitching for forming the loops and picotting of all the cut edges therein desirable or necessary for the construction of seamless kimonos subsequently severed from said bolt, in numbers limited only by the length of the fabric contained in such bolt, and whereby in the manufacturing of seamless kimonos for the market another and less skilled person may be employed for splitting the hemstitching, connecting the opposing loops with the ribbons, leaving in position for a third and artistic operator to form the decorative bows, and as a result of which the cost and time required for the construction of seamless kimonos are accordingly reduced, and this especially when the fabric of a kimono consists of crêpe de chine, and similarly thin, flimsy materials.

In conclusion it may be observed that my invention is not limited to the details of construction or material herein shown and described, for that my invention includes a kimono of any material, the back and front parts of which consist of a transversely folded seamless strip of textile fabric provided with a number of opposing loops adapted for the passage therethrough of strips of any suitable fabric capable of detachably securing opposing surfaces of the fabric in the shape required for a kimono.

Having described my invention, what I claim and desire to secure by Letters Patent is:

1. A kimono, the back and front parts of which consist of a transversely folded seamless strip of textile fabric, provided with a number of spaced loops opposing and in register with each other, and with strips passing through said loops, and thereby adapted for detachably connecting and securing the meeting edges of said strip together and shape the garment to the wearer.
2. A kimono, having a closed back and divided front part, consisting of a transversely folded seamless strip of textile fabric provided with a number of spaced loops adjacent their opposing side edges formed integral with the fabric, and strips passing through said loops detachably connecting said back and front parts.
3. A kimono, the back and front parts of which consist of a transversely folded seamless strip of textile fabric, provided adjacent the opposing side edges thereof from their bottom edge to about the hip line with a series of spaced loops extending at a right angle to said edges, a number of strips adapted to pass through and connect said loops, longitudinal loops located adjacent said edges in register with each other at the waist line, and one or more longitudinal loops located about the center of the back in a plane substantially above the waist line, and a sash passing through said longitudinal loops, the tightening of which conforms the kimono to the figure of the wearer, and distends the folded edge to a form simulating sleeves.
4. A kimono, the back and front parts of which consist of a transversely folded seamless strip of textile fabric, provided with means for detachably connecting the longitudinal side edges thereof, and with a cross

cut in the front part adjacent the back part forming corner pieces, adapted to be folded outwardly, and means for detachably securing said folded corner pieces to the front part and to the form of a collar for the neck of the wearer.

5. A kimono, provided with a closed back and divided front parts, consisting of a transversely folded seamless strip of textile fabric having a number of spaced loops adjacent the side edges thereof, and at the middle of the back part above the waist line of the wearer, provided with corner pieces at the neck portion by a cross cut at a right angle to and through the meeting edges of the front portion, said front portions and corner pieces being respectively provided with tongues adapted to register with each other, and means passing through said several slits adapted to connect together the back and front parts, the corner pieces in a folded condition to the front part and to adjust the kimono to and conform it to the bust of the wearer.

6. A kimono, the back and front parts of which consist of a single transversely folded seamless strip of textile fabric constructed with a front opening and a number of slits forming loops constructed from hemstitching the fabric along the lines of their respective locations, and thereafter splitting the hemstitch whereby said edges are picoted, and the loops are adapted for the passage of strips of ribbon assembling and shaping the garment.

In witness whereof, I have hereunto set my hand and affixed my seal, this 12th day of April, A. D. 1916.

VIRGINIA MARIE ELLIOTT. [L. S.]
